UNITED STATES PATENT OFFICE.

CHARLES WM. SCHUMANN, OF NEW YORK, N. Y.

DESIGN FOR A BOX.

SPECIFICATION forming part of Design No. 17,351, dated May 17, 1887.

Application filed February 26, 1887. Serial No. 229,046. Term of patent 7 years.

To all whom it may concern:

Be it known that I, CHARLES W. SCHUMANN, of the city, county, and State of New York, have invented and produced a new and original Design for a Box, of which the following is a specification.

Reference is to be had to the accompanying drawing, forming a part of this specification, in which the figure represents a view in perspective of a box embodying my new design.

The leading feature of the design consists in a box representing an old or worn and broken-down shoe, substantially as hereinabove described and claimed.

15 A represents a box, which is in the form of an old or worn and broken-down shoe. This box A, when viewed in perspective, as illustrated, shows an old or worn shoe at full length, and so that the under side of its sole a and heel b and its upper portion, including the side d, which is represented as more or less broken down, are fully exposed. The worn condition of the shoe is depicted in part by an irregular figure, c, in the tread or under side of the sole a of the shoe, extending to its side, which figure is designed to represent a hole worn in the bottom of the outer sole of the shoe, and likewise in the inner sole thereof, the former hole being of greater area than the latter.

30 The realistic effect of the old-shoe-like box is further augmented by a figure, D, upon the under side of the heel, at the rear end, extending to its edge partially at the sides and embracing the entire rear edge, which figure is

designed as a representation of a worn-down heel, wherein the successive layers constituting a heel are exposed in ragged outline.

The old-shoe-like box may also have its simulating effect augmented by figures e on the sole or sole and heel of the shoe, representing nail-heads, the figures e upon the heel being so arranged as to constitute in appearance a fastening for the worn and ragged layers of figure D.

45 The cord-like lines or figure h on the upper portion of the shoe represent a lace or lacing.

I claim—

1. In a design for a box, consisting of a body simulating an old or worn and broken-down shoe, the figure D on the rear under side of the heel, extending to the side and rear edges and representing the successive layers of the heel as worn down, as herein shown and described.

55 2. In a design for a box, consisting of a body simulating an old or worn and broken-down shoe, the figure e on the under side of the sole, extending to the side of the shoe and representing a hole worn in the outer and inner sole, and the figure D on the rear under side of the heel, extending to the side and rear edges, representing the successive layers of the heel as worn down, as herein shown and described.

CHAS. WM. SCHUMANN.
